MULTISTACK NESTED ARTICLE
DISPENSING APPARATUS

James D. Reifsnyder and Albert F. Miller, Flushing, N. Y., assignors to Lily-Tulip Cup Corporation, New York, N. Y., a corporation of Delaware

Application October 9, 1943, Serial No. 505,608

18 Claims. (Cl. 312—44)

This invention is dispensing apparatus of the multi-stack or magazine type wherein cup-shaped articles are dispensed successively in an axial direction from a given stack of nested articles, and when such stack has been depleted a fresh stack is moved into dispensing position. The invention is particularly useful in dispensing nested articles, such as cups and the like, from nested stack formation, and the invention will be described, by way of illustration, with reference to apparatus especially adapted for dispensing paper drinking cups.

In apparatus of this general type, the main purpose is to accommodate a greater number of articles than can be conveniently or practically arranged in a single stack. Therefore, the stacks are kept to a convenient height and in the case of paper cups, which are packed in nested condition in cartons (usually containing 100), it is convenient and customary to use the nested cups thus packed as the unit stack. By providing for multiple stacks of such height, a device of suitable height is possible, but the utilization of a plurality of relatively short stacks presents certain difficulties which have not been overcome heretofore. These difficulties are more especially critical in devices for handling stacks of nested articles, such as paper drinking cups.

For example, it has been proposed to arrange stacks of nested articles on a carrier for movement about a common center and dispensing articles, such as cups, from the bottom of one of the stacks until the said stack has been depleted, and thereafter delivering a succeeding stack from the carrier to the dispensing station. In such an arrangement, however, the carrier could not be moved in a rearward direction for reloading purposes until the depletion of the active stack, nor could the carrier be moved in the direction of feed until such depletion took place. Accordingly, in such a device, the attendant would have to wait until the entire magazine was empty or until that instant when an active stack has been depleted and before a fresh stack is fed from the carrier to the dispensing station, before the carrier could be moved for purposes of loading. Thus, from a service standpoint, it was first necessary to remove the cups by hand from the active stack, or to have access to all stack spaces in the magazine, so that those which happened to be empty could be refilled; and accordingly in practice such magazines were refilled from the top, which necessitated exposing the interior of the magazine by removal of its cover and required a free height above the mag-

azine greater than the height of the stacks to be inserted. On the other hand, if loading in an axial direction was not utilized, access to the entire circumference or perimeter of the magazine and removal of all parts of any surrounding casing would be required. These difficulties are especially serious in certain uses, as where the apparatus is to be employed in conjunction with a beverage dispensing device, which in usual practice is entirely enclosed in a unitary cabinet. It is important for the foregoing reasons to provide for loading of such cup dispensers at a loading or filling station through a relatively small opening and to provide for filling one or all of the empty magazine spaces without interference with the active stack and regardless of the size of said stack.

Furthermore, in the accommodation of an unusually large number of stacks, heretofore difficulty has been experienced in keeping the size and contour of the magazine within reasonable proportions and this difficulty is increased when said ready access for loading is desired, and more especially so in connection with drinking cups which, for sanitary reasons, should not be touched from the time of manufacture until the time of use.

The present invention provides for the desirable features and overcomes the difficulties, both above indicated, and provides a sturdy and dependable mechanism which is reliable in operation over relatively long periods of use without necessitating repairs or adjustments.

Various further and more specific objects, features and advantages will more fully appear from the following description taken in connection with the accompanying drawings which form a part of this specification and illustrate, by way of example, present preferred embodiments of the invention.

The invention consists of the novel features, arrangement and combination of parts embodied by way of example in the apparatus hereinafter described as illustrating present preferred forms of the invention, and the invention will be more particularly pointed out in the appended claims.

Referring to the drawings:

Fig. 1 is a plan view, partly in cross-section along the line 1—1 of Fig. 2, illustrating an embodiment of the invention employing two turrets for accommodating a plurality of stacks of cups disposed in a sinuous path.

Fig. 2 is a front elevational section of the device shown in Fig. 1, taken along the line 2—2 of Fig. 3, with certain parts broken away.

Fig. 3 is a plan view showing certain driving mechanism of the device of Fig. 1 as viewed from beneath.

Fig. 4 is a side elevation showing certain parts of the device shown in Figs. 1 and 2.

Fig. 5 is a plan view, partly in cross-section taken along the line 5—5 of Fig. 8 showing an embodiment of the invention wherein the stacks of cups are disposed about a single turret.

Fig. 6 is a plan view showing certain driving mechanism of the device of Fig. 5, being a cross-section taken at the line 6—6 of Fig. 8.

Fig. 7 is a cross-sectional view taken at the line 7—7 of Fig. 8 showing further details of said device.

Fig. 8 is a front elevation, partly in section, of the device shown in Fig. 5.

Fig. 9 is a view similar to that shown in Fig. 1, illustrating a somewhat modified form of arrangement for supporting the stacks of cups in a two-turret device.

Fig. 10 is a plan view showing somewhat diagrammatically a device in which four turrets are employed for holding a relatively large number of stacks in a sinuous path and illustrates a further modification of the device.

Referring more particularly to Figs. 1 and 2: The device comprises in general a supporting structure designated in general as 1, which in the present embodiment is shown as a pedestal support, but which may be a part of a beverage dispensing apparatus in which the invention is adapted to be employed; a suitable cup dispensing unit 2 for dispensing individual cups, and which in the present embodiment is illustrated as the dispenser described and claimed in Reifsnyder and Miller Patent No. 2,263,421; December 30, 1941; and a magazine or reservoir, designated in general as 3, for holding a supply of cups arranged in vertical stacks to be fed as required to the dispensing unit 2 at such time as the stack in register with said unit has been depleted to a predetermined degree.

The supporting structure 1 comprises a suitable base 4 which has rigidly secured thereto upwardly extending legs, such as 5, 6, 7 and 8, which rigidly carry a supporting plate 9. The plate 9 carries rigidly secured thereto a vertically upwardly extending journal sleeve 10 which passes upwardly through an opening in the plate 9 and whose lower end carries integrally formed therewith, as by welding, a flange 11 which is rigidly secured to the lower face of the plate 9. The journal sleeve 10 carries adjacent its upper end a suitable anti-friction bearing, such as 12, which serves as a supporting bearing for a vertical spindle 13 whose lower end is held centrally within the bearing sleeve 10 by a suitable bearing, such as 14. The upper end of the spindle 13 is provided with a flange 15 to which is rigidly secured the hub of a turret 16.

For convenience of assembly, the turret 16 comprises an upper section 17 and a lower section 18 joined together at the flange 15 by screws 19 and screw rods 20, the latter of which also serve to rigidly secure to the bottom of the portion 18 a plate shelf 21 which serves as a bottom support for the stacks, designated S, of nested cups C. In the preferred embodiment, the stacks are bodily supported vertically, and are carried horizontally and partially supported laterally by the turret 16. The turret 16 (Fig. 1) is provided with peripherally disposed longitudinally extending recesses 22 circumferentially spaced so as to provide therebetween outwardly extending longitudi-

nally disposed projecting portions 23. The cross sections of recesses 22 throughout the vertical extent of the section 17 conform to a radius somewhat larger than the radius of the maximum diameter of the cups to be dispensed (see also Fig. 2), and in the lower section 18, this radius decreases downwardly in general conformity with the taper of the cup.

Disposed rearwardly of the turret 16 (Fig. 1) is a second similar turret 16a suitably mounted on the plate 9 in the manner similar to that previously described so that its axis of rotation is parallel to that of the turret 16. The axes are spaced apart so that when respective recesses 22 of one turret are oppositely disposed to the respectively cooperating recesses of the other turret, the space provided therebetween serves to accommodate a stack of cups. A suitable casing is provided for the turrets comprising side wall sections designated in general respectively as 24 and 25 (Fig. 1), and a top or cover section 26 (Fig. 2). The side wall section 24 is supported by posts 27, 28 and 29 whose lower ends are rigidly secured to and extend upwardly from the plate 9, as shown in Fig. 2. The side wall is spaced outwardly from the turret 16 so as to provide a space between the side wall and the recesses 22 slightly wider than the diameter of the cups to be dispensed, except at the bottom of the side wall where there is provided an inwardly extending wall portion 30 which, in the present embodiment, is conveniently made of wood having an inner face conforming in general to the taper of the cup. The upper portion of the side wall above the block 30 is made of sheet material, such as metal or, preferably, a transparent plastic material. The sheet wall section 24 is provided with a door portion 31 hinged along a vertical pivot 32 and provided with a releasable catch 33 engageable with the post 29; thus providing an opening for filling the magazine with a fresh supply of stacks of cups, as will be more particularly pointed out hereinafter. The rear section 25 is similarly supported on posts, such as 34, 35, 36 and 37, and is similarly spaced with respect to the turret 16a as previously described in connection with the first turret. This section is similarly provided with a lower wall portion, such as 38, which forms a continuation of the side wall as previously described in connection with the block 30. For the purposes to be hereinafter more fully apparent, a cup slide shoe 39 (Fig. 1) is secured to the plate 9 between the converging arcs defined by the turrets 16 and 16a to the left of their axes and the corresponding shoe 40 is similarly disposed to the right of their axes, these shoes having their upper surfaces on a plane with the upper surface of the cup support plates 21 and 21a, so that the bottom of the stacks of cups carried on the turrets will be held at the proper level during the transfer from one turret to the other, and tapering downwardly and outwardly toward their outer ends toward the level of the plate 9. A cup slide shoe 41 is similarly secured to the plate 9 adjacent the periphery of the turret 16 contiguous the dispensing unit 2. This shoe at its left end tapers upwardly from adjacent the level of the table 9 for a portion of its length and its right-hand portion has an upper surface disposed in the plane of the upper surface of the turret plate 21; so that as a stack is fed forward toward the dispensing unit 2, the plate 41 serves to maintain the bottom of the stack on a level feed plane and also acts as a base for loading stacks. A cup deflector cam

42 is secured at its right-hand end to the supporting plate 9 and projects to the left into an annular groove provided in the turret portion 18 (Fig. 2), so as to extend into the path of movement of a stack of cups and thereby serve to deflect said stack from its path of travel on the turret into register with the dispensing unit 2. An arcuate stop or abutment wall 43 is secured at its forward end to the post 29 and extends rearwardly and around to the left so as to provide a vertical wall disposed circumferentially in register with the dispensing unit 2, thereby serving as a positive stop for a stack of cups being fed by the turret into the dispensing unit.

Since the cup dispenser unit 2 is fully shown and described in said Patent No. 2,268,421, a detailed description will not be necessary; but only such features thereof will be described as are useful in explaining its operation in conjunction with other features of the present invention. The dispenser 2 is provided with an inlet throat 44 (Fig. 1) to receive the lower end of a stack of cups from which individual cups are to be dispensed. Projecting into the inlet throat are a plurality of stack supporting and cup dispensing cam members, such as 45, which are actuated by a dispensing arm 46. In the particular dispensing unit herein shown, rearward (anti-clockwise) movement of the arm 46 dispenses a cup and forward (clockwise) movement of the arm resets the device for the next operation and lowers the stack an increment of movement corresponding to the spacing between adjacent cups of the stack; therefore, a complete cycle of operation of the arm 46 comprises first a rearward movement of the arm to the extent of its travel and the return movement of the arm to its initial position. The cups so individually dispensed fall out through the discharge throat 47.

ACTUATING MECHANISM

Referring more particularly to Fig. 3, it will be seen that the lower end of the spindle 13 carries rigidly secured thereto a gear 48 which is in mesh with an idle gear 49 which in turn is in mesh with an idle gear 50 which is in mesh with a gear 51 (see also Fig. 2) rigidly secured to the lower end of the spindle 13a. A pinion gear 52 is also rigidly secured to the lower end of the spindle 13a and is in driven engagement with a gear 53 which is journaled on a stud shaft 54 supported on the underside of the plate 9. A pinion gear 55 is rigidly secured to the gear 53 and is in mesh with a gear segment 56 formed integrally with a gear arm 57 which is pivotally mounted on a stud shaft 58 rigidly supported on the underside of the plate 9. The arm 57 carries a pair of stud pins 59 to which are secured corresponding ends of a pair of helical tension springs 60 whose opposite ends are anchored to the supporting plate 9 as by a pair of stud bolts 61. The turret spindle 13a also carries rigidly secured thereto, interposed between the gears 51 and 52, an escapement wheel 62 carrying a plurality of teeth, such as 63, equal in number to the number of recesses 22 in the turret 16. An escapement pawl 64 is pivotally supported from the plate 9, as at 65, and is provided with a pair of detents, such as 66, for alternate engagement with the teeth 63, so that in a complete reciprocation of the arm 64 back and forth, one of the detents 66 will release one of the teeth 63 and the other detent 66 will catch the succeeding tooth during one throw of the arm 64, and the reverse throw of the arm 64 will release the tooth

63 from one detent 66 and catch it on the other detent 66, i. e. the complete reciprocation back and forth of the arm 64 will permit two increments of movement to the escapement wheel 62 aggregating the angular space between two of the teeth 63. It will, therefore, be seen that under the driving power of the springs 60, upon reciprocation of the arm 64 back and forth, the turrets 16 and 16a will be caused to rotate in synchronism the angular distance corresponding to the displacement of one stack of cups. The escapement pawl 64 is actuated by a solenoid 67 whose armature is connected to the pawl 64 by means of a suitable linkage 68.

15 Electric current is supplied to the solenoid 67 by suitable means (not shown), and the circuit is controlled by a suitable switch, such as a "micromatic" switch 69 (Fig. 2) rigidly secured to the frame 1 by means of screws 70 (Fig. 4).

20 The switch 69 is actuated by an engaging pin 71 adjustably carried on the outer end of an arm 72 pivotally mounted on the frame by means of a gudgeon bolt 73. To insure closing of the switch 69, the arm 72 is preferably urged downwardly by a light leaf spring, such as 74, which is anchored by the bolt 73. The arm 72 is provided on the opposite side of its pivot with a downwardly extending "feeler" finger 75 which is held in retracted or outward position by the stack of 30 cups at the dispensing station in register with the dispensing unit 2. The lower end of the finger 75 is positioned below the upper surface of the turret plate 21; and the distance between the lower end of the finger and the cams 45 of 35 the dispensing unit 2 determines the number of cups remaining in the dispensing unit at the time that a fresh stack of cups is fed into register with the dispensing unit 2. It will therefore be seen that, upon a predetermined diminution of 40 the stack of cups at the feeding station, in so far as the active stack is concerned, the finger 75 is permitted to move inwardly, and the switch 69 to be closed to complete the circuit to the solenoid 67. It is desirable to have the finger 75 releasably held from engagement with the stack normally, so as to avoid resistance against the cups and interference with free dropping of the stack downwardly in the dispensing unit. In order to accomplish this, provision has been 45 made to lock the arm 72 in raised position so as to hold the switch 69 open during the intervals between the dispensing of individual cups from the unit 2. This is provided for by the cam plate 76 (see also Fig. 4) which is mounted on a fixed 50 pivot 77 and is restrained in its travel by the screws 70 which are disposed in corresponding slots provided in the cam plate 76. The lower edge of the cam plate 76 is provided with a cam surface 78 which rests on the dispensing arm 46 55 so that upon the forward motion (return stroke) of the dispenser arm 46, the cam plate 76 is raised and its upper edge 79 engages the arm 72 to hold the same in raised position; conversely, as the dispensing arm 46 is moved rearwardly (dispensing stroke), the arm 72 is permitted to move downwardly into engagement with an active 60 stack, or beyond provided the stack of cups has been sufficiently depleted to clear the finger 75. This release and locking of the finger 75 takes 65 place at each individual dispensing of a cup from the dispensing unit 2 and avoids any interference with the proper axial feed of an active stack in the dispensing unit 2 and thus prevents interference with the proper operation of the unit 70 2. This is particularly important where a dis-

pensing device of this character is utilized as a part of a beverage dispensing machine wherein at each actuation of the beverage dispensing machine a cup must be disposed in position to receive the beverage being dispensed. This arrangement also provides a convenient control for use in loading.

OPERATION

Loading

Referring more particularly to Figs. 1 and 2; the dispensing device is initially loaded with a supply of stacks of nested cups, as follows: With the dispensing arm 46 in its forward position to prevent closing the relay circuit, the door 31 is opened and a stack of cups is inserted in an adjacent recess 22 of the turret 16 with the bottom of the stack resting on the turret plate 21 and shoe 41. In order to load the cups into the device without having the operator's hands touch the cups, it is preferable to open the bottom of the container or carton in which the cups are packed in nested form, and insert the end of the container in the open door and allow the stack to slide into position; and by gradually raising the carton and slipping the top of the stack inwardly as it passes out of the carton, the stack may be readily inserted laterally through the side opening and beneath the top or cover 26. The operator then rotates the turret 16 in a clockwise direction by means of a suitable hand-wheel 80 (Fig. 2) which is held in driving engagement with the turret by suitable means including a screw rod 81, which passes through the hub of the turret and is in screw-threaded engagement with the upper end of the spindle 13, thus permitting ready removal of the hand-wheel 80 so that the cover 26 may be removed for purposes of inspection or such cleaning of the interior of the casing as may be desired from time to time. It is noted, however, that the device is so constructed and arranged that the cups are substantially fully protected against dust and dirt from the exterior. Such rotation of the hand-wheel 80 causes the next succeeding recess 22 to be brought opposite the filling opening provided by the open door 31; and a second stack is inserted as above described. The operation is continued by successive rotation of the turret. By means of the gear train (Fig. 3), the clockwise rotation of the turret 16 is accompanied by the anti-clockwise rotation of turret 16a in step with the turret 16. After the third recess 22 has been filled in the turret 16, and as the turret is rotated during the next step, the bottom of the stack first inserted in the turret passes over the cup slide shoe 39 to assure the positioning at the bottom of the stack in the plane of the upper surface of the turret plates 21 and 21a, and as the next succeeding stack is inserted in the turret 16, the first stack is positioned between oppositely disposed recesses of the turrets 16 and 16a. It will be noted that as the bottom of the stack is engaged by the shoe 39, it is deflected towards the axis of the turret 16 by a portion of the side wall 24 adjacent the post 28, to thereby guide the cup toward its transfer position. Upon the next step of rotation of turret 16, the first stack loaded into said turret is deflected from turret 16 by means of that portion of the side wall 25 contiguous the posts 36 and 37, and during this transfer, the cup slide shoe 40 serves to maintain the bottom of the stack thus being transferred in the plane of the turret plate 21a. The cups are successively loaded into the

recesses 22 of turret 16 and successively transferred to turret 16a until nine stacks have thus been loaded into the supply mechanism. During this reverse or loading rotation of the turrets, the 5 rotation of the spindle 13a (Fig. 3), through a gear train 52—53—55—56, has moved the arm 57 in a clockwise direction to tension the springs 60, and one of the detents 66 engages a tooth of the escapement wheel 62 to hold the parts in 10 the position indicated.

Feeding stacks to dispensing station

A stack of cups is now fed to the dispensing unit 2 by moving the dispensing arm 46 rearwardly to lower the cam plate 76 to the solid line position of Fig. 4 and thus permit the arm 72 to move downwardly, and since no active stack is yet in place, the spring 74 now moves the arm 72 downwardly to close the switch 69 and energize the solenoid 67 (Fig. 3) which moves the arm 64 in a clockwise direction to release one of the teeth 63 and engage a succeeding tooth 63, thus effecting a first increment of movement. The dispensing arm 46 is now moved forwardly to the dotted position (Fig. 4) thereby lifting the cam plate 76 and causing the arm 72 to move upwardly to open the switch 69 and deenergize the solenoid 67, whereupon spring 68a returns the arm 64 to the position shown in Fig. 3, thus causing one detent 66 to release a tooth and the other detent 66 to engage said tooth so as to effect the second increment of movement. The said two increments of movement thus cause the turret to move one index step or angular distance corresponding to the angular displacement of one stack. During this step of movement, the cup slide shoe 41 engages the bottom of the stack being fed to the dispensing station and raises it to the level of the turret plate 21, which relieves 20 the stack of frictional engagement with the wall of the casing 24 and assures alignment of the stack vertically. The cup deflector cam 42 deflects the stack outwardly from its recess, and the stack is thus discharged from its curvilinear path of travel past the turret projection 23 and over the throat 44. Due to the tapered shape of the cups, the register of the stack at the discharge station is facilitated and the stop 43 serves to assure accurate vertical alignment of the cups 30 for about half of the circumference of the stack, and the turret portion 23 adjacent the discharge station is so disposed as to come to rest adjacent the periphery of the stack opposite the stop plate 43 so as to effect registration and prevent any 40 possibility of the stack falling away from the plate 43. As the stack comes into register, it falls downwardly until the rim of the lowermost cup rests upon the cams 45 of the dispensing unit 2. If it is desired to completely fill the magazine 50 so as to replace the stack fed into the dispenser 2, this may be done initially in the manner to be described following under "Reloading."

Upon the forward movement of turret 16 to feed cups to the dispensing unit, the recesses 60 in the turret 16 as they successively become empty (i. e., as said recesses move past and beyond the dispensing station) are filled with stacks of cups which are transferred thereto from the turret 16a in a manner similar to that previously 70 described heretofore relative to the loading. That is, as the turrets are rotated in the forward or feed direction, a stack is deflected from turret 16a by means of that portion of the side wall 24 contiguous the post 28, and during this transfer 75 the cup slide shoe 39 serves to maintain the bot-

tom of the stack, thus being transferred, in the plane of the turret plate 21.

Reloading

At any time, when desired, the magazine may be refilled or supplied with stacks of cups regardless of the length of the stack of cups at the dispensing station and without in any manner interfering with the stack at the dispensing station, the lower end of which stack is engaged within the dispensing unit 2. This is one of the main features of the invention and is of particular importance in permitting the supply of cups in the magazine to be replenished at such time as the device is reached for servicing. For example, in devices of this general type where provision is made to feed a fresh stack to the dispensing station after a predetermined diminution of the active stack, there will always be present in the active stack a sufficient number of cups to bring the height of the stack above the bottom of the other stacks in the magazine. As soon as the active stack is depleted, a fresh stack will be supplied to the dispensing station. Accordingly, at no time when the magazine is to be replenished with a fresh supply of stacks will the active stack of cups have been diminished to a height below the level of the stacks in the magazine. For this reason, it has heretofore been necessary to load the magazines of devices of this general type from the top, i. e. axially, or to have access around the entire periphery of the magazine, and this is impractical in many instances, more especially where the dispensing unit is to be used in a limited or enclosed space, such as in the cabinet of a beverage dispensing unit.

In the present invention, however, this difficulty has been overcome by offsetting the dispensing station so that the means for supplying the cups thereto from the magazine may operate forwardly or rearwardly while a stack is present at the dispensing station. By referring to Figs. 1 and 2, it will be seen that if the magazine is to be reloaded with one or more additional stacks, the turret 16 may be moved in a clockwise direction as previously described to bring the turret cavity or recess 22 past the dispensing station to the filling station, and by opening the door 31, a fresh stack may be placed in the empty cavity, and any succeeding empty cavities in the magazine may be similarly filled by successive movements of the turret in a direction reverse to the feeding direction. As the fresh stacks are fed into successive recesses in the turret 16, the preceding stacks are successively fed in an anti-clockwise direction by the turret 16a. For example, when the machine is initially loaded, and after the first stack has been deposited at the filling station, the turret 16 may be moved in a clockwise direction so that the recess from which a stack has been fed to the filling station may be refilled, at which time the device will contain ten stacks of cups, one in the dispensing unit 2, four in the turret 16, one jointly carried by the turrets 16 and 16a, and four carried in the turret 16a.

Dispensing

As previously indicated, individual cups may be dispensed downwardly in an axial direction from the active stack (Fig. 1) by moving the dispensing arm 46 rearwardly, and upon the return movement of the dispensing arm the device is then positioned for the next dispensing opera-

tion. Upon the rearward or dispensing stroke of arm 46, if the stack has become depleted sufficiently, the feeler 75 moves inwardly and a fresh stack is fed forward to the dispenser unit 2 in the manner above described. However, if the active stack has not been so depleted, the feeler 75 engages the active stack and serves to hold the arm 72 upwardly against the action of spring 74, thereby preventing the energization of the relay.

As is well-known in the art, when the apparatus is utilized as a part of a beverage dispensing unit, the dispensing arm, such as 46, will be actuated by suitable mechanism in timed relation with the beverage dispensing mechanism in order that the cup dispensed may receive the beverage. For this reason, in such use of the apparatus, it is especially important that a large supply of cups be provided for in the magazine so that the cup will likewise be available without too-frequent servicing.

MODIFICATION (FIGS. 5-8 INCL.)

In Figs. 5-8 inclusive, an embodiment of the invention is disclosed in which a single turret is employed and in which a slightly modified form of turret drive is provided; otherwise the essential features are similar to those previously described. In order to avoid undue duplication, a detailed description will be omitted of such parts of this embodiment as are identical with or substantially identical with the embodiment previously described, and such parts will be designated by the same numerals as the corresponding parts of Figs. 1-4 inclusive with a prime suffix added.

Referring more particularly to Figs. 6 and 8, the turret spindle 13' carries rigidly secured to its lower end an escapement wheel 62' which is engageable with the detent portions 66' of the escapement pawl 64', pivotally supported on the outer end of an arm 65' which is rigidly supported from the plate 9' by means of the sleeve 10'. The pawl 64' is attached by means of a linkage 68' to the armature of solenoid 67', in the manner similar to and for the purposes previously described in the foregoing embodiment. The pawl 64' in Fig. 8 is shown moved to a position opposite that shown in Fig. 6, to better show the parts in elevation. The turret spindle 13' also carries rigidly secured to its lower end a driving arm 82, the outer end of which is attached to one end of a convolute spring 83 which rests on a spring wheel 84, and the inner end of the spring 83 is anchored to said wheel by a fixed stud. The wheel 84 is rigidly mounted on a hanging bracket 85 rigidly secured to the supporting frame and extends downwardly from the supporting plate 9'. It will thus be seen that upon rotation of the turret 16' in a clockwise direction (Fig. 5), the spring 83 is placed under driving tension, and after the turret has been rotated to the degree desired, one of the detents 66' engages the face of one of the teeth 63' to prevent feed movement of the turret 16' in an anti-clockwise direction. The turret 16' is loaded by inserting stacks through the side opening provided by opening the door 31' (Fig. 5), and the turret 16' is successively rotated step by step in a clockwise direction until the turret is filled similar to the manner previously described (in the present embodiment, five stacks are held in the turret), and in the event that it is attempted to bring the remaining sixth recess 22' opposite the filling station, the inner end of the plate 43' prevents the

continued movement of the turret by engaging with the stack of cups in the succeeding space 22'. As in the previous embodiment, the turret may be given a feeding movement by manipulation of the dispenser arm 46' to its rearward position to cause the turret to feed a stack of cups into the dispensing unit 2', and thereafter upon returning the dispensing arm 46' to its forward position, the turret may be rotated in a clockwise direction to bring the recess from which the stack has thus been ejected to the filling station, and a stack of cups can then be inserted; whereby the apparatus will contain five stacks in the turret and one at the dispensing station.

It is noted that in Fig. 8, the active stack is shown as having been depleted to a point permitting the finger 15' to move inwardly, thus permitting the switch 69' to close in a manner previously described in connection with the previous embodiment, and this is the point in the cycle of operation at which the solenoid 67' (Fig. 6) is energized to start the feeding step of the turret 16'. Relay 67' is shown de-energized in Fig. 6 for purposes of clarity.

MODIFICATION (FIG. 9)

Instead of having the stacks bodily vertically supported on the turrets, as in the previous embodiments, other features of the invention previously described have been embodied in apparatus wherein the cups are not bodily supported by the turrets but rest upon a feed table over which they are moved by the turrets. Fig. 9 illustrates such a device wherein the various parts are arranged and disposed as previously described in the embodiment of Figs. 1-4 inclusive, except as more particularly pointed out following herein-after. The supporting plates, such as 21 and 21a of Figs. 1-4, have been omitted from the turrets and the stacks of cups rest in a sinuous groove 86, of a width slightly greater than the bottom of the cup and having side walls conforming in general to the taper of the cup (as indicated by the double lines of the groove 86) comparable to the inner wall of the block 30 (Fig. 2). Accordingly, when the magazine is filled, the bottom of the stacks will rest in the groove and be supported by the bottom of the groove and will be disposed within the recesses of the respective turrets which, together with the surrounding casing, will support the stacks laterally. The recesses in the turret of this modification are shown with straight walls, instead of the lower portions being tapered as in Figs. 1-4; but it is to be understood that the tapered form may be used if desired. In this modification, the bottoms of the stacks remain on substantially the same plane defined by the bottom of the groove 86, and hence no slide shoes (such as 39, 40 and 41 of Fig. 1) are needed; and the contour of the groove path at the region 81 is such as to deflect the bottom of the stack outwardly from its curvilinear path and into the opening 88 of the dispensing unit (not shown) thus obviating the necessity for a deflector cam (such as 42 of Fig. 1). This embodiment of the invention is not considered as desirable as the embodiment previously described because of the friction encountered in moving a number of stacks and the possible damage to the bottoms of the cups in moving along a supporting track, such as the bottom of the groove 86; but this embodiment has been successfully operated.

MODIFICATION (FIG. 10)

The invention lends itself to almost unlimited

possibilities respecting the number of cups accommodated in the magazine and the configuration (in plan view) of the magazine casing or outer contour. For example, in Fig. 10, there is somewhat diagrammatically illustrated an embodiment of the invention in which the stacks are disposed in a long sinuous path which passes successively around four centers, such as 101, 102, 103 and 104, corresponding to the axes of turrets arranged as disclosed in the previous embodiment (Figs. 1-4) a casing, designated in general as 105, serving to define the boundary of said path of travel and to protect the stacks, as hereabove set forth. The active stack, at the dispensing station, is designated as 106, the feed path is designated by the sinuous dot line and the ejection path by the dot-dash line. By arranging the axes of the respective turrets, in the desired geometric order, the configuration of the casing 105 in plan view can be varied to fit various requirements as to space. It will be understood by those skilled in the art, after understanding the invention, that the four turrets about centers 101-104 inclusive are interconnected for synchronous movement and that the other details of construction and operation will be in accordance with the previous description.

From the foregoing, it will be seen that the invention is applicable to apparatus comprising one or a relatively large number of turrets and that the diameter of the turrets may be proportioned in accordance with the size of the articles being dispensed and the number of stacks desired to be carried by each turret up to a maximum diameter which may be accommodated in the desired space. Furthermore, when a very much larger number of stacks is to be provided for than may be carried conveniently in one group about a central axis, the invention provides for an arrangement of the stacks in a sinuous path which may be made to follow such a course as is desired, to fall within the compass of a given space. Furthermore, whether the stacks are arranged about a common center as in a one-turret device, or about a plurality of centers as in a multi-turret device, the magazine may be refilled through a relatively small side opening without disturbing the active stack, regardless of its length, and without necessitating the touching of the cups or stacks by the operator servicing the equipment.

Having thus described our invention with particularity with reference to the preferred embodiment of the same, and having referred to some of the possible modifications thereof, it will be obvious to those skilled in the art, after understanding our invention, that other changes and modifications may be made therein without departing from the spirit and scope of the invention, and we aim in the appended claims to cover such changes and modifications as are within the scope of the invention.

What we claim is:

1. In a multi-stack dispensing device for nested articles, the combination of means for supporting and moving in a curvilinear path a plurality of vertical stacks of nested articles to be dispensed, means for individually dispensing said nested articles successively from a vertical stack offset laterally from said path, and means for transferring successive stacks from said path to said dispensing means.

2. In a multi-stack dispensing device for nested articles, the combination of means for supporting and moving in a sinuous path a plurality of

vertical stacks of nested articles to be dispensed, means for individually dispensing said articles successively from the bottom of a vertical stack offset laterally from said path, and means for transferring successive stacks from said path to said dispensing means.

3. In a multi-stack cup dispensing device for nested articles, the combination of means for supporting and moving in a curvilinear path a plurality of vertical stacks of nested cups to be dispensed, said means comprising a rotatable carrier defining the inner limit of said path and having portions for driving engagement longitudinally of said respective stacks, and guide means spaced outwardly from said carrier and defining the outer limit of said path, means for disengaging successively said stacks from driven engagement by said rotatable carrier and positioning said successive stacks at a dispensing station, and cup dispensing means in register with said station positioned for dispensing individual cups from the lower end thereof successively.

4. In a multi-stack dispensing device for nested articles, the combination of means for supporting and moving in a curvilinear path a plurality of vertical stacks of nested articles to be dispensed, said means comprising a carrier rotatable forwardly and rearwardly defining the inner limit of said path and having portions for driving engagement longitudinally of said stacks and a side wall spaced outwardly from said carrier and defining the outer limit of said path, means for disengaging successively said stacks from driven engagement by said carrier during its forward rotation and moving said successive stacks beyond the periphery of said carrier, article dispensing means disposed to receive the lower end of said stacks as they are successively disengaged from said carrier, said side wall having an opening longitudinally of said carrier for the passage of successive stacks therethrough to said carrier, whereby said carrier may be rotated rearwardly past a stack in dispensing position and said carrier reloaded with stacks.

5. In a multi-stack dispensing device for nested articles, the combination of a rotatable turret provided with peripherally disposed axially extending recesses for respective stacks of nested articles to be dispensed, said recesses being adapted to receive said stacks radially of said turret, means for holding said stacks in said recesses during a part of the cycle of rotation of said turret, means for positioning successive of said stacks beyond the periphery of said turret at a dispensing station during another part of said cycle, and a dispensing unit positioned at said dispensing station for successively dispensing individual articles from stack in said station, said turret being rotatable in a reverse direction past the dispensing station to thereby successively refill empty recesses in said turret without interference with the articles at the dispensing station.

6. In a multi-stack dispensing device for nested cups, the combination of a vertical turret mounted for rotation in forward and reverse directions and provided with peripherally disposed axially extending recesses for respective stacks of nested cups, said recesses being adapted to receive said stacks radially of said turret, means for rotating said turret in a forward direction intermittently, means for holding said stacks in said recesses during a part of the cycle of forward rotation of said turret means for positioning successive of

said stacks beyond the periphery of said turret at a dispensing station during another part of said cycle, a dispensing unit positioned at said dispensing station for successively dispensing individual cups from the lower end of a stack in said station, said turret being rotatable in a reverse direction past the dispensing station to thereby successively refill empty recesses in said turret without interference with the cups at the dispensing station, and means for controlling the intermittent forward rotation of said turret, said control means comprising a laterally movable feeler member mounted adjacent said dispenser unit for yielding engagement with the outer periphery of cups of the respective stacks at said dispensing station.

7. In a multi-stack dispensing device for nested articles, the combination of a rotatable turret for supporting nested articles in a plurality of vertical stacks arranged in a circuitous series, means for rotating said turret to advance said stacks to a dispensing station, a dispenser unit for dispensing individual articles successively from the bottom of a stack at said dispensing station, said unit being offset laterally from said turret so that a stack at said station will be positioned out of the path of movement of said turret, and means for guiding said stacks in a curvilinear path and successively to said station.

8. In a multi-stack dispensing device for nested articles, the combination of a plurality of rotatable turrets for supporting nested articles in a plurality of vertical stacks arranged in a sinuous-series, means for rotating said turrets forwardly to advance said stacks to a dispensing station adjacent one of said turrets, a dispenser unit for dispensing said articles successively one at a time from the bottom of a stack at said dispensing station, said unit being offset laterally from said adjacent turret so that a stack at said station will be positioned out of the path of movement of said turret, and means for guiding said stacks in a sinuous path and successively to said station.

9. In a multi-stack cup dispensing device for nested cups, the combination of a dispensing unit for successively dispensing individual cups from the bottom of a stack of nested cups, a magazine having fixed substantially vertically extending guide walls formed of curved sections and movable means for jointly holding and feeding a series of vertical stacks of nested cups forwardly along a substantially horizontally disposed and laterally sinuous path laterally offset adjacent the outer extremity of which said dispensing unit is secured to said magazine means for arresting the forward travel of the foremost of said stacks and positioning the same in register with said dispensing unit, said magazine having a side filling opening providing access thereto, said movable means being operable in a reverse direction independently of the number of cups in the stack in register with said dispensing unit, whereby said magazine may be filled through said opening by the reverse movement of said movable means while a stack of cups is in register with said dispensing unit.

10. In a multi-stack dispensing device for nested articles, the combination of a turret mounted for rotation about a vertical axis and provided with axially extending peripherally spaced outwardly projecting portions between which respective stacks of nested articles are adapted to be received, a casing spaced outwardly from said turret and providing means for holding said stacks in position about said turret, a

discharge throat for receiving the lower end of a stack of said articles to be dispensed and through which said articles are adapted to pass, said throat being laterally offset relative to said turret so that a stack in register with said throat will be disposed beyond the outer diameter of said turret, and means for guiding successive of said stacks into register with said throat and out of the path of rotation of said turret.

11. In a multi-stack dispensing device for nested articles, the combination of a turret mounted for rotation about a vertical axis and provided with axially extending peripherally spaced outwardly projecting portions between which respective stacks of nested articles are adapted to be received, a casing spaced outwardly from said turret and providing means for holding said stacks in position about said turret, a discharge throat for receiving the lower end of a stack of said articles to be dispensed and through which said articles are adapted to pass, said throat being laterally offset relative to said turret so that a stack of said nested articles in register with said throat will be disposed beyond the outer diameter of said turret, and means for guiding successive of said stacks into register with said throat and out of the path of rotation of said turret, said casing being provided with a refill opening disposed axially of said turret and through which individual stacks may be inserted in the spaces between said turret portions, whereby said turret may be rotated in a rearward direction past a registered stack and empty turret spaces may be brought past said opening and stacks successively placed in said spaces.

12. In a multi-stack dispensing device for nested articles, the combination of a turret mounted for rotation about a vertical axis and provided with axially extending peripherally spaced outwardly projecting portions between which respective stacks of nested articles are adapted to be received, a casing spaced outwardly from said turret and providing means for holding said stacks in position about said turret, a discharge throat for receiving the lower end of a stack of said articles to be dispensed and through which said articles are adapted to pass, said throat being laterally offset relative to said turret so that a stack in register with said throat will be disposed beyond the outer diameter of said turret, means for guiding successive of said stacks into register with said throat and out of the path of rotation of said turret, and means for rotating said turret step by step for respective registration of successive stacks with said throat and for positioning successive turret projections adjacent said registered stack delivered to said throat, whereby said projection provides a vertical support for said registered stack.

13. In a multi-stack dispensing device for nested articles, the combination of dispensing mechanism for successively dispensing said nested articles one by one from the lower end of a vertical stack of said articles in active position and thereby decreasing the height of said stack by successive increments, means for holding a plurality of stacks in inactive position and moving successive of said stacks to said active position upon predetermined diminution of said active stack, mechanism for controlling said movement comprising a member disposed for engagement with the outer wall of an active stack, said member being urged inwardly toward said stack for engagement therewith and being disposed a predetermined distance

above said dispensing mechanism, and means for inhibiting the inward movement of said member during that period in the actuation of said dispensing mechanism at which said incremental decrease takes place, whereby upon said active stack being diminished to a predetermined height said member moves inwardly, thereby causing a successive stack to be moved from inactive to active position during an interval between the dispensing of individual articles.

14. In a dispenser for cup-shaped articles, a plurality of holding means, each capable of holding a plurality of stacks of nested articles to be dispensed and constructed and arranged to advance the stacks from one holder to the other in the operation of the dispenser, a dispensing station, and means for transferring the stacks of nested articles from one of said holding means to said dispensing station.

15. In a dispenser for cup-shaped articles, a plurality of rotatable turrets constructed and arranged to hold a plurality of stacks of nested articles to be dispensed and to advance such stacks from one turret to another in the operation of the dispenser, a dispensing station located adjacently outside the periphery of one of said turrets and means for successively transferring the stacks of nested articles from such turret to said dispensing station.

16. In a dispenser for cup-shaped articles, a plurality of rotatable turrets constructed and arranged to hold a plurality of stacks of nested articles to be dispensed and to advance such stacks from one turret to another in the operation of the dispenser, a dispensing station located adjacently outside the periphery of one of said turrets, a sinuous track defining the path of movement of the stacks and supporting such stacks as they are advanced to the dispensing station, and means for successively transferring the stacks from one of said turrets to said dispensing station.

17. In a dispenser for cup-shaped articles, rotatable means provided with a plurality of radially extending members forming a plurality of recesses adapted to receive stacks of nested articles to be dispensed, means for intermittently rotating said means to cause said members to advance the stacks positioned therebetween, a dispensing station located adjacently outside the outside radius of said members, means for maintaining the stacks between said members as they are being advanced towards said dispensing station and means for successively shifting the stacks from between said members to said dispensing station during the movement of said members.

18. In a dispenser for cup-shaped articles, a plurality of rotatable turrets, each provided with radially extending portions forming a plurality of vertically disposed recesses adapted to receive stacks of nested articles to be dispensed, said turrets being so constructed and arranged that the vertical recesses of one turret will successively come into opposed registered relation with the respective recesses of another turret during the rotative movements of such turrets, means for transferring a stack disposed in opposed registered recesses from one turret to another as such recesses move from their opposed relation, a dispensing station adjacent to a receiving turret and means for successively shifting the stacks from such turret to said dispensing station.

JAMES D. REIFSNYDER.
